UNITED STATES PATENT OFFICE.

LUTHER T. DUNNING, OF AULANDER, NORTH CAROLINA.

FIFTH-WHEEL FOR VEHICLES.

1,171,708.

Specification of Letters Patent. Patented Feb. 15, 1916.

Application filed March 30, 1915. Serial No. 18,077.

To all whom it may concern:

Be it known that I, LUTHER T. DUNNING, a citizen of the United States, residing at Aulander, in the county of Bertie and State 5 of North Carolina, have invented new and useful Improvements in Fifth-Wheels for Vehicles, of which the following is a specification.

This invention relates to improvements in 10 fifth wheels for wagons and other vehicles, the object of the invention being to provide an improved fifth wheel which serves to automatically lock the front axle and the front bolster whenever the tongue is at ex- 15 actly right angles to the front axle, so as to prevent the tongue or the front axle from turning when one of the front wheels drops into a hole or rut or passes over a stone or other obstruction in the road, and which is 20 automatically operated by the tongue, when turning the vehicle in any direction, to free the front axle by releasing it from the front bolster.

The invention consists in the construction, 25 combination and arrangement of devices hereinafter described and claimed.

In the accompanying drawings, Figure 1 is a plan of the front portion of the wagon 30 running gear provided with a fifth wheel and tongue constructed and arranged in accordance with my invention. Fig. 2 is a vertical longitudinal sectional view of same. Fig. 3 is a detail vertical transverse sectional view of the fifth wheel, and with 35 tongue shown in section and the pawls shown partly in section. Fig. 4 is a detail horizontal sectional view of parts shown in Fig. 3. Fig. 5 is a detail perspective view partly in section, of the engaging ends of 40 the pawls.

For the purpose of this specification the front axle of a wagon is indicated at 1, the front bolster at 2 and the reach at 3. The front wheels are indicated at 4. The front 45 end of the reach is pivotally connected to the center of the bolster by the king bolt 5.

The fifth wheel comprises, in accordance 50 with my invention, an upper member 6 and a lower member 7. These members are here shown as segments. The upper member is secured to the end side of and extended rearwardly from the bolster 2. The lower member 7 is secured to the upper side of and extended rearwardly from the front axle 1. 55 The king bolt 5 passes through an opening

in the tongue 8, at a point a considerable distance from the rear end of the tongue. Hence the tongue is pivotally mounted and is permitted limited pivotal play independent of the front axle. The rear end of the tongue is arranged and allowed to play in a transverse slot or recess 9 in the center of the lower fifth wheel member 7 and the tongue is provided on its upper side, at a point immediately in front of said member 65 7 with a tappet plate 10 the ends of which as here shown, project beyond opposite sides of the tongue. Any form of tappet may be provided, and if wide enough, the tongue may form its own tappet. 70

The upper fifth wheel member 6 is provided with a pair of concentrically arranged racks 11—12, the former in front of the latter, and the teeth of said racks incline in opposite directions and are reversely arranged. 75

A pair of reversed U-shaped pawls 13—14 are provided and adapted to engage the racks 11 and 12. These pawls are arranged reversely to each other, astride the upper member 6 and with their lower ends pivotally mounted on bolts 15. The pawl 13 is provided with a lug 16 at one side for engaging the teeth of the rack 11 and the pawl 14 has a similar lug 17 for engaging the teeth of the rack 12. The tongue is arranged with its front rear portion between the pawls so that when the wagon is running on a straight line along a road the front axle is parallel with the front bolster, both of the pawls are engaged with the racks hence the upper and lower members of the fifth wheel are locked together by the coaction of the pawls and the racks, said fifth wheel members serving to lock the front 80 85 90 95 axle to the front bolster. 100

Hence if one of the front wheels passes over a stone or other obstruction in the road or drops into a hole or rut in the road the front axle is prevented from turning on the king bolt as it is locked with the front bolster and the tongue hence is not turned on either side. When, however, the tongue is turned to one side or the other by the team, as when turning the vehicle, the tappet disengages one of the pawls from one of the racks and the other pawl, is permitted to slip idly on its rack, thus unlocking the lower fifth wheel member from the upper member and enabling the lower fifth wheel member to turn with the 105 110

front axle, as required, independent of the upper fifth wheel member and of the front bolster.

When the tongue is turned in either direction out of a position at right angles to the front axle, it releases one of the pawls, and the other pawl remains in place to promptly receive any sudden turn in the opposite direction. One of the pawls always stays locked, no matter in which direction the tongue is turned. Springs 19 prevent the pawls from rattling.

In the drawings I show braces 18 which connect the reach to the front bolster.

15 While I have herein shown and described a preferred form of my invention I will have it understood that changes may be made in the form, preparation and construction of the several parts without departing 20 from the spirit of my invention and within the scope of appended claims.

Having thus described my invention, I claim:

1. In a vehicle, the combination of the 25 front axle and front bolster, a tongue, a pivotal element connecting the axle and bolster and tongue together for independent angular movement, the fifth wheel presenting a lower member attached to the axle and the upper member attached to the bolster, and means pivotally mounted on the lower

fifth wheel member and adapted to engage with the upper pivotal wheel member, said means being reversely arranged on opposite sides of the tongue and adapted to be disengaged by the tongue when the latter is turned in either direction. 35

2. In a vehicle, the combination of the front axle, the front bolster, a tongue, a pivotal element connecting the axle, and bolster 40 and tongue together for independent angular movement, a fifth wheel comprising a lower member attached to the axle and an upper member attached to the bolster, said lower member having concentrically arranged racks the teeth of each are reversely arranged, the pawls pivotally mounted on the lower fifth wheel member and adapted to engage the racks of the upper fifth wheel member, said pawls being reversely arranged and on opposite sides of the tongue and adapted to be disengaged by the tongue when the latter is turned in either direction, both of said pawls normally engaging the racks and coacting therewith to normally 50 lock the fifth wheel members together.

In testimony whereof I affix my signature in presence of two witnesses.

LUTHER T. DUNNING.
